CLAIM

The ornamental design for an end fitting for a cable cover, as shown and described.

DESCRIPTION

FIG. 1 is a perspective view of an end fitting for cable cover, showing my new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof; and,

FIG. 9 is a perspective view of the end fitting fitted to a cable cover covering a charging cable.

The broken lines in the drawing depict unclaimed environmental subject matter that forms no part of the claimed design.
